(57) **CLAIM**

The ornamental design for a rim of car steering wheel as shown and described.

DESCRIPTION

FIG. 1 is a perspective view of a rim of car steering wheel showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is a partial enlarged view of portion 9 in FIG. 1; and, FIG. 10 is a partial enlarged view of portion 10 in FIG. 2. The dash-dot-dash broken line encircling the sectional view are for annotative purpose only and form no part of the claim design.

1 Claim, 10 Drawing Sheets
